(57) **CLAIM**

The ornamental design for a docking station, as shown and described.

DESCRIPTION

FIG. 1 is a front perspective view of a docking station showing our new design.

FIG. 2 is a front view thereof.

FIG. 3 is a cross-sectional view thereof along line 3-3 shown in FIG. 2.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The short broken lines showing the remaining portions of the docking station illustrate features of the article of manufacture that form no part of the claimed design.

The broken lines consisting of dot-dash lines are boundary lines that show that the claimed design extends to the boundary line, but does not include the boundary line.
